UNITED STATES PATENT OFFICE.

BUEL H. CANADY, OF WINSLOW, ARIZONA.

REMOVABLE BEARING-PLATE.

1,387,588.

Specification of Letters Patent. Patented Aug. 16, 1921.

Application filed August 14, 1920. Serial No. 403,500.

To all whom it may concern:

Be it known that I, BUEL H. CANADY, a citizen of the United States, residing at Winslow, in the county of Navajo and State 5 of Arizona, have invented certain new and useful Improvements in Removable Bearing-Plates, of which the following is a specification.

My invention relates to journal boxes for 10 railway locomotives, trucks, trailers or the like, and has particular reference to improvements in removable bearing lateral plates, disclosed in my co-pending application for removable bearing plates filed January 15, 1920, Serial No. 351,681.

An important object of the invention is to provide laterally extending lugs carried by the removable bearing plate and box, which lugs are so constructed and shaped 20 that their inclined contacting faces have the maximum area, and accordingly increased strength in supporting the bearing plate and holding it against lateral displacement.

Other objects and advantages of the invention will be apparent during the course 25 of the following description.

In the accompanying drawings forming a part of this specification, and in which like numerals are employed to designate like 30 parts throughout the same,

Figure 1 is a transverse section taken on line 1—1 of Fig. 2,

Fig. 2 is a side elevation of apparatus embodying my invention,

Fig. 3 is a longitudinal section taken on line 3—3 of Fig. 1, and,

Fig. 4 is a perspective view of the box and bearing plate, separated,

In the drawings, wherein for the purpose 40 of illustration is shown a preferred embodiment of my invention, the journal box or driving box embodies a box or body portion 5, including an upper arch 6 and legs 7. The box 5 is provided at its ends with flanges 8. This box may be of any well known or preferred type, and is arranged in the usual manner on the pedestal of the truck frame, or the like. The numeral 9 designates an 45 arch bearing, formed of bearing metal, such as brass or Babbitt metal. The arch bearing is held within the arch 6 in the usual manner.

The numeral 10 designates a vertically removable end bearing plate, which is adapted 50 to be arranged in contacting relation with the flange 8. This end bearing plate has

its outer side provided with a bearing strip 11, which may be formed of brass, Babbitt metal, or any other suitable material. The bearing strip 11 may be secured to the plate 60 10 in any suitable manner, as by means of a dove-tail joint 12, or by any other suitable means.

The flange 8 adjacent to the vertically removable end bearing plate carries a pair 65 of laterally or horizontally outstanding lugs 13, rigidly secured thereto, and these lugs have their upper faces 14 beveled or inclined downwardly toward their inner ends, with the points 15 at their outer ends projecting 70 outwardly beyond the flange 8, for substantial distances. In other words, the lugs 13 have a substantially greater width than the flange 8, with their inner ends flush with the inner side of the flange, and their outer 75 ends projecting forwardly or outwardly beyond the outer face of the flange 8, for a substantial distance. This construction increases the length of the inclined contact faces 14. Upper coacting laterally or horizontally outstanding lugs 16 are rigidly secured to the vertical edges of the end bearing plate 10, and extend laterally and inwardly beyond the same, for a substantial distance, with their outer ends flush with 85 the outer face of the bearing plate. The upper lugs 16 have lower inclined contact faces 17, extending from the forward end to the rear end thereof, and these inclined faces extend downwardly toward the inner 90 portion of the box. The inclined faces 17 are adapted to engage the inclined faces 14, and these faces are of the same length.

The lugs 13 and 16 are provided with vertical openings 20, slightly larger in diameter than bolts 21, pass therethrough, whereby these bolts may be readily withdrawn, and the upper lugs may partake of restricted or limited lateral movements with relation to the lower lugs. The lower ends 100 of the bolts 21 are screw-threaded, to engage nuts 22, and a cotter pin 23 is preferably passed through an opening in the lower end of each bolt.

The numeral 24 designates a wheel, having a hub 25, slidably engaging the strip 11. 105

The removable end bearing plate 10 is provided in its top with an opening 26, for receiving a lubricant. This opening leads into a transverse opening 27, to supply the 110 lubricant to the face of the strip 11. I also contemplate applying the thickness of the

plate 10, preferably upon its top, as at 26' so that when this plate is removed and a new plate substituted or the old one re-babbitted or rebrassed, it will not be necessary to measure the width of the plate desired, as this will be ascertained from the marking of the old plate.

In use, when the strip 11 becomes worn, the nuts 22 may be removed from the bolts 21, and the end bearing plate 10 raised vertically, and separated from the box 6. Another end bearing plate may be substituted in its place or the old one re-babbitted or rebrassed.

I also contemplate applying my invention to the ordinary box or wheel face bearing now in use, in which event the outer end of the box or wheel face should be faced off for one-half to one and one-half an inch to provide a space for the bearing plate. The lugs 13 may be suitably secured to the flange 8 of the box, by welding or the like.

It is to be understood that the form of my invention herewith shown and described is to be taken as a preferred example of the same, and that various changes in the shape, size, and arrangement of parts may be resorted to without departing from the spirit of my invention, or the scope of the subjoined claims.

Having thus described my invention, I claim:

1. The combination with a journal box having an outer flange, of laterally extending lugs carried by the flange and extending longitudinally beyond the outer face of the flange for a substantial distance, said lugs having inclined upper faces and substantially vertical openings, a vertically movable bearing plate to engage the flange, laterally extending lugs carried by the bearing plate and extending longitudinally inwardly beyond the inner face of the bearing plate for a substantial distance, the second named lugs having lower inclined faces extending from their outer ends to their inner ends and adapted to engage with the first named inclined faces, said second named lugs having substantially vertical openings, and bolts passing through the openings of the first and second named lugs.

2. The combination with a journal box having a flange near one end, of laterally

extending lugs secured to the flange and extending longitudinally beyond one face of the flange for a substantial distance, said lugs having upper inclined faces extending throughout substantially their entire length and substantially vertical openings, a vertically movable bearing plate to engage the flange, laterally extending lugs carried by the bearing plate and extending longitudinally beyond one face of the bearing plate for a substantial distance, said second named lugs having lower inclined contact faces extending throughout substantially the entire length of the lugs and adapted to engage the first named inclined faces, the second named lugs having substantial vertical openings, and bolts passing through the openings of the first and second named lugs.

3. The combination with a journal box, of laterally extending lugs secured thereto near one end thereof, and having upper inclined contact faces extending throughout substantially the entire length of the lugs, a vertically movable bearing plate to be arranged adjacent to the end of the journal box, laterally extending lugs carried by the plate and extending longitudinally beyond one side of the plate for a substantial distance, the second named lugs having lower inclined contact faces extending throughout substantially the entire length of the same and adapted to engage the first named inclined faces, and means to draw the sets of lugs toward each other.

4. The combination with the journal box, of laterally extending lugs secured thereto near one end thereof, and having upper inclined contact faces extending throughout substantially the entire length of the lugs, said lugs having openings formed therein, a vertically movable bearing plate to be arranged adjacent one end of the box, lateral extending lugs carried by the bearing plate and extending longitudinally beyond one face thereof for a substantial distance, the second named lugs having lower inclined contact faces extending from their outer ends to their inner ends and adapted to engage the first named inclined faces, the second named lugs having openings formed therein, and bolts engaging in said openings.

In testimony whereof I affix my signature.

BUEL H. CANADY.
